DESIGN FOR A POLICE SIGNAL BOX

Edward A. Brass, Shreveport, La.

Application April 9, 1945, Serial No. 118,935

Term of patent 14 years

(Cl. D72—1)

To all whom it may concern:

Be it known that I, Edward A. Brass, a citizen of the United States, residing at the city of Shreveport and State of Louisiana, have invented a new, original, and ornamental Design for a Police Signal Box, of which the following is a specification, reference being had to the accompanying drawing, forming a part thereof.

I claim:

The ornamental design for a police signal box, as shown.

EDWARD A. BRASS.
